UNITED STATES PATENT OFFICE.

ALFRED T. STURDEVANT, OF CROTON FALLS, NEW YORK.

HAT-BODY-ROUNDING MACHINE.

SPECIFICATION forming part of Letters Patent No. 298,795, dated May 20, 1884.

Application filed September 29, 1883. (No model.)

To all whom it may concern:

Be it known that I, ALFRED T. STURDEVANT, a citizen of the United States, residing at Croton Falls, in the county of Westchester 5 and State of New York, have invented certain new and useful Improvements in Hat - Body-Rounding Machines; and I do hereby declare the following to be a full, clear, and exact description of the invention, such as will enable 10 others skilled in the art to which it appertains to make and use the same.

My invention relates to certain novel and useful improvements in machines for rounding hat-bodies, and has for its object to provide 15 such a machine which shall effect a uniform shear cut, while at the same time it may be so adapted that hat-bodies of various sizes may be accommodated, or the cut may be made to any desired depth; and with these ends in view 20 my invention consists in the details of construction and combination of elements herein-after fully and in detail explained, and then specifically designated by the claims.

In order that those skilled in the art to which 25 my invention appertains may understand more fully its construction and operation, I will proceed to describe the same, referring by letters to the accompanying drawings, forming part of this specification, in which—

30 Figure 1 is a plan view of my improvement, illustrating more particularly the platform upon which the hat-body is clamped; Fig. 2, a view showing the platform and mechanism for adjusting the same in section and the cutting-disks and means for operating the same in side elevation; Fig. 3, a detail view of the cutting-disks in operative position; and Fig. 4, a detail view of the traveling block, showing the graduated scale.

40 Similar letters of reference denote like parts in the several figures of the drawings.

A is the bed-plate of the machine, having projecting therefrom standards B, within which are journaled the shafts C D in any ordinary way.

E is a driving-pulley mounted, preferably, on the upper shaft.

50 F are cog-wheels mounted on said shafts so as to mesh, the object of this construction being to communicate motion from the upper shaft to the lower.

G are cutting-disks secured on the inner extremities of the said shafts in such manner as to make a shear cut.

H is an elongated slot within the bed-plate, 55 and within this slot is a traveling block, I, to the bottom of which is secured or cast integral therewith a nut, J, for the purpose presently explained.

K is a platform or table, of any suitable shape 60 or contour, and swivelly connected at its rear portion to the top of the traveling block I.

L is a threaded rod journaled within bearings M and operating within the nut J. This rod is confined as against longitudinal movement by means of collars N. The threads in the nut and on the rod are in the same direction, but of the opposite nature, so that it will be readily understood that the action of the rod within the nut will slide the block back 65 and forth, as the case may be. For convenience in manipulation I secure a wheel, O, on the rod, as shown.

P Q are gages, by means of which hat-bodies of different sizes may be accommodated. These 75 gages consist of plates of metal or other suitable material slotted longitudinally and arranged to slide on the surface of the platform or upon proper bearings, as may be desired, and clamped in any required position by means of set-screws R, passing through said slots or otherwise arranged so as to bear directly upon the said plates. Along the line of movement of these gages I preferably make a graduated scale, by means of which the 80 adjustments for hat-bodies of different sizes may be determined.

S is a spring-clamp, underneath which is placed the hat, as shown at Fig. 1, and by means of which the hat-body is firmly held 85 during the operation of cutting.

The operation of my improvement is as follows: I raise the said clamp and insert the hat so that the peaked or tip part shall abut against the gage P, and the sides be confined 95 by the gages Q, as clearly shown at Fig. 1. If a large hat-body is to be operated upon, I run the gage P backward to accommodate the depth of the hat-body and likewise adjust the gages Q to allow for the width. The traveling block is then adjusted by means of the rod L, as hereinbefore set forth, in order to bring 100

the platform in its revolution nearer to or farther away from the cutting disks for the purposes of taking a greater or less cut, as may be desired. The platform is then swung toward 5 the revolving cutting disks, and the lower portion of the hat-body which protrudes is fed between said disks and cut on a perfect arc. No feeding of the hat-body by hand between the cutters is necessary after the latter have once 10 come in contact with the hat-body, because they will continue to draw the hat-body toward them until it has been entirely cut around.

Prior to my invention hat-bodies have been 15 rounded by cutting off by hand with knives; but this is not only tedious and expensive, but the cut so formed is not regular or the same in all cases, and additional trimming is generally required.

By the use of my improvement the manufacture 20 of hats is not only cheapened, but a better class of work is produced. Should the cutters become dull, they may be readily removed and sharpened or new ones substituted therefor.

25 Having thus described my invention, what I claim as new, and desire to secure by Letters Patent, is—

1. In a device for rounding hat-bodies, the combination of means for holding the hat-body 30 flat upon a revolving platform and the cutting mechanism, substantially as set forth.

2. In a device for rounding hat-bodies, means for holding the hat flat in its cone shape upon

the platform, and adjustable gages for confining the hat as against horizontal displacement, 35 substantially as set forth.

3. In a device for rounding hat-bodies, the swiveled platform adapted to support the hat, in combination with means for clamping the hat flat in its cone shape against said platform, adjustable gages to prevent horizontal displacement of the hat, and mechanism for cutting the hat-body, substantially as and for the purpose set forth. 40

4. The table K, swivelly attached to the adjustable block I, and having secured thereto the clamp S and gages P Q, in combination with the cutters G, substantially as shown and described. 45

5. The clamp S and gages P Q, attached to 50 the platform, as shown, whereby the hat-body may be held and different sizes accommodated, in combination with means for adjusting said platform and mechanism for cutting the hat-body, substantially as described. 55

6. The clamp S and gages P Q, attached to the platform, as shown, whereby the hat-body may be held and different sizes accommodated, substantially as set forth.

In testimony whereof I affix my signature in 60 presence of two witnesses.

ALFRED T. STURDEVANT.
